US0D1003671S

(12) **United States Design Patent** (10) **Patent No.:** **US D1,003,671 S**
(45) **Date of Patent:** **** Nov. 7, 2023**

(54) **GRILL PRESS**

(71) Applicant: **Yangjiang Yangdong Xingtai Hardware Wooden Manufacture LLC.**, Yangjiang (CN)

(72) Inventor: **Guixing Liu**, Yangjiang (CN)

(73) Assignee: **Yangjiang Yangdong Xingtai Hardware Wooden Manufacture LLC**, Yangjiang (CN)

(**) Term: **15 Years**

(21) Appl. No.: **29/831,874**

(22) Filed: **Mar. 23, 2022**

(30) **Foreign Application Priority Data**

Mar. 16, 2022 (EM) 008886261-0002

(51) **LOC (14) Cl.** **07-04**

(52) **U.S. Cl.**

USPC **D7/669**; D7/368; D7/682

(58) **Field of Classification Search**

USPC D7/359, 368, 372, 393, 395, 401.2, 403, D7/407, 408, 409, 414, 500, 601, 602, D7/614, 629, 664, 665, 667, 668, 669, D7/670, 672, 673, 674, 675, 678, 682, D7/697, 703; D5/53; D8/18, 34, 40; D21/455

CPC .. F23H 17/12; A47J 37/00; A47J 37/07; A47J 43/281; A47J 37/067; A47J 37/06; A47J 43/20; A47J 37/108; A47J 43/28; A22C 7/0076; A22C 9/008; B41F 1/02; F16L 37/127; A21C 15/007; D06C 11/00; B26B 25/005

See application file for complete search history.

(57) **CLAIM**

The ornamental design for a grill press, as shown and described.

DESCRIPTION

FIG. 1 is a perspective view of a grill press, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 shown in FIG. 1.

1 Claim, 9 Drawing Sheets
